AUTOMOBILE TORPEDO.

1,360,036.

Specification of Letters Patent. Patented Nov. 23, 1920.

Application filed January 20, 1920. Serial No. 352,649.

To all whom it may concern:

Be it known that I, HAROLD W. SHONNARD, residing at Upper Montclair, in the county of Essex and State of New Jersey, a citizen 5 of the United States, have invented or discovered certain new and useful Improvements in Automobile Torpedoes, of which improvements the following is a specification.

The invention has for its primary object 10 the provision of means whereby the speed and effective range of automobile torpedoes may be greatly increased. Other improvements will hereinafter appear.

Numerous difficulties are encountered in 15 materially increasing the speed of torpedoes above that developed by those in present use owing to the limited permissible size and weight of the torpedo. For example, to increase the speed of a torpedo having the 20 present standard maximum dimensions from one of thirty to one of forty knots per hour, would necessitate practically doubling the propelling power. If a larger shell should be used in order to accommodate a power 25 unit having an increased capacity, no material advantage would be obtained, by reason of the fact that increase of resistance due to the enlarged cross-sectional area and wetted surface would nearly offset the increase 30 in propelling power.

A further difficulty developed when a torpedo is driven through the water at high speed is that cavitation becomes a serious factor, the zone at the stern in which there 35 is no body of water frequently expanding until only the extreme tips of the blades remain in water upon which they may exert a propulsive action. This condition not only reduces the propelling efficiency of the 40 power unit, but also has a tendency to cause the torpedo to roll and thus disturb the steering mechanism and alter the course of the torpedo. When a torpedo is steering a curved course the effects of cavitation in the 45 vicinity of the propellers are accentuated, due to the fact that the zone of cavitation follows the curve and thus exposes the blades on one side of the axis of the torpedo to a cavity and those on the opposite side to a 50 body of water.

The effects of cavitation are minimized in the preferred embodiment of the present invention by the steadyng influence of a pair of propellers located at the bow of the torpedo and rotating in opposite directions

about its longitudinal axis. These propellers operate in practically undisturbed water and exert a steadyng influence upon the stern propellers, with which they may be positively connected, if desired, by means 60 of suitable shafting and gears. Propulsion losses, due to the slip of the stern propellers when they are operating in a cavity, are compensated by the increased propulsive action of the bow propellers, for the reason that 65 when the stern propellers are unloaded the turbine speed will increase until the bow propellers assume the load removed from the stern propellers. It will be apparent therefore that a substantially uniform velocity 70 will be maintained under conditions encountered at high speed, and because of the steady movement, the torpedo will follow its intended course with greater precision than has been heretofore attained. The invention 75 however is not limited to the use of both bow and stern propellers.

By the present invention the motor and transmission mechanism of the torpedo are so organized and combined as to operate to 80 the greatest advantage, so that by a much more effective utilization of the available space I am enabled to produce a torpedo of permissible dimensions which will run at a much higher speed and will have a greater 85 effective range than those heretofore used. Features of the invention contributing to this end are: a compact turbine motor having two separate single-stage rotors disposed one on each side of a central driving-shaft, so that 90 they are statically balanced and no ballast is required; a compact reduction gearing connecting the rotors with the driving-shaft or shafts and disposed between the spaced rotors, so that the gearing is also statically 95 balanced; shielding of the gearing from the turbine rotors, so that the heated operating gases cannot come in contact with the gearing; the provision of oppositely rotating coaxial propellers at the bow of the torpedo, 100 supplementing those usually employed at the stern, whereby greater power may be translated into propulsive action; the provision of means for cooling the exhaust gases before they are passed through the 105 stern propeller shaft; and such other features as will hereinafter appear.

In the accompanying drawings, Figure 1 is a longitudinal horizontal section through the forward portion, and Fig. 2 a like sec- 110

tion through the rear portion, of a torpedo embodying the invention in its preferred form. Figs. 3, 4 and 5 respectively illustrate modifications.

5 Referring first to Figs. 1 and 2, the torpedo body as a whole is divided longitudinally into four sections, the war-head 6, the motive-fluid flask 3, the after-body 10 and the tail-section 17, by suitable bulkheads 7, 10 4, 5, 11, 12 and 18. The rear bulkhead 7 of the war-head is provided with a hollow cylindrical extension 9 opening at its front into the hollow shaft tube 8, which projects forwardly through the war-head. The extension 9 forms a casing for gearing carried by the bulkhead 4 of the motive-fluid flask, which will be hereinafter described. The war-head contains the explosive charge 6', which is detonated by a suitable fuse, 20 not shown.

At the forward end of the after-body 10 there is arranged concentrically within the torpedo-shell a cylindrical wall 15' suitably secured to the bulkhead 11 and opening 25 rearwardly; and closing the space between the cylindrical wall 15' and the shell is an annular transverse wall 15, thus forming at the forward end of the after-body 10 an annular compartment 14 in which are mounted 30 the rotors of the turbine motor to be presently described, so that the hot exhaust gases from the rotors are excluded from contact with the reduction gearing, which is mounted in and contiguous to the 35 closed compartment 13 between the rotors. The fore bulkhead 11 of the after-body is so disposed with relation to the rear bulkhead 5 of the motive-fluid flask 3, that a space 16 is left between them. At the rear 40 of the after-body 10 there is also a space 19 between the rear bulkhead 12 of the after-body and the fore bulkhead 18 of the stern section 17.

The motor of the torpedo comprises a 45 pair of high-power single-stage impulse turbine rotors 20 and 21, disposed in the annular compartment 14 of the after-body 10 on opposite sides of the longitudinal axis of the torpedo, and adapted to rotate about 50 a transverse axis. The rotors 20 and 21 are mounted upon separate shafts 22 and 23, respectively, which are journaled in bearings 24 carried by a suitable frame 25. The frame 25 is supported within the cylindrical 55 partition 15' in any suitable way.

The frame 25 also supports a longitudinally disposed bearing 26 concentrically with the longitudinal axis of the torpedo, in which is journaled a central stub-shaft 27 60 having a watertight bearing at its forward end in the bulkhead 11. The journal openings of the bearings 24 communicate with the openings of the bearings 26, and consequently these gearings may be readily lubricated from a single source. Coaxially

with the stub-shaft 27 a central shaft 28 extends aft, being journaled at its forward end in a fixed transverse stud 29 having oppositely extended transverse shaft-arms 30 and 31 secured at their outer ends to the 70 frame 25. The forward end of the shaft 28 is also supported in a bearing 32 in a plate 33, which is bolted to extensions 34 of the frame 25. The rear end of the shaft 28 is journaled in a bearing 35 carried by the 75 rear bulkhead 12 of the after-body 10, and is provided with a packing gland 36 to prevent exhaust gases from entering the after-body 10 from the rear chamber 19, into which they flow as hereinafter described. 80 The shaft 28 projects beyond the bulkhead 12, and is provided with a hollow shaft-coupling 37 having openings 38 through which the exhaust gases in the space or chamber 19 may pass to the inner hollow propeller 85 shaft 39, which is attached to the coupling 37, and which therefore forms an extension of the shaft 28 through the stern section 17. The adjacent ends of the shafts 28 and 39 are provided with keys 40 adapted to engage 90 slots in the coupling 37 in such manner that the shafts may be coupled by a longitudinal movement when the stern section 17 and the after-body 10 are moved into assembled relation. 95

As has already been stated, the reduction gearing connecting the turbine rotors with the shafting which drives the propellers is arranged between the rotors and within the central cylindrical compartment 13. This 100 gearing comprises pinions 71 and 72 secured to the rotor-shafts 22 and 23, respectively, at points between their respective rotors and the central stub-shaft 27. The pinions 71 and 72 mesh with reduction gears 73 and 74, 105 respectively, which are respectively mounted upon the stud shafts 30 and 31. The gears 73 and 74 are centrally provided with small bevel gears 75 and 76, which mesh, respectively, with bevel gears 77 and 78, keyed 110 to the shaft 28 and the stub-shaft 27. From the foregoing it will be apparent that the rotors 20 and 21 are positively connected by the gear chain just described, and must therefore rotate at equal 115 velocities. The shaft 39 in the stern section, which, as already stated, is coupled to the rear end of the shaft 28, is journaled at its forward end in a bearing 41 in the bulkhead 18 and in a stationary stud 42 having 120 oppositely extending shaft-arms 48' supported by the wall of the section 17. The rear end of the hollow shaft 39 is journaled in a hollow outer concentric shaft 43, which is in turn journaled in a stern bearing 44 125 at the rear end of section 17. The shafts 39 and 43 are the propeller shafts. The outer shaft 43 extends beyond the stern section 17, and the propeller 45 is keyed upon its projecting end. The inner shaft 39 pro- 130

jects beyond the end of the shaft 43, and the propeller 46 is keyed upon its projecting end and held against displacement by a suitable nut 47, having an orifice 48 in alignment with the passage through the hollow shaft 39.

From the foregoing description it will be seen that it is characteristic of the construction and arrangement of the mechanism described, that the two single-stage turbine rotors 20 and 21 are disposed on opposite sides of the longitudinal axis of the torpedo in statically balanced relation, while the reduction gearing connecting the rotors with the shafting which drives the propellers is arranged between the rotors and symmetrically of the longitudinal axis of the torpedo, so that said gearing is also statically balanced. By this arrangement I am enabled to obtain greatly increased driving power per unit of motive fluid, with but little, if any, increase in the weight of the torpedo, since no ballast is necessary. A further distinguishing feature is that of providing for the gearing a compartment completely shielded from the rotors, and centrally arranged thereof as above described; so that the heated exhaust gases are effectively excluded from contact with the gearing.

In the construction shown and described the gaseous motive fluid, which has preferably been superheated, is discharged from the flask 3 through the port 80 in the bulkhead 5, which may be connected with the turbine nozzles 79 by any preferred form of connection, not shown. The gases discharged from the nozzles pass through the blading of the turbine, and after giving up their energy to the rotors, are exhausted into the annular chamber 14, whence they are conducted through the opposite exhaust conduits 80' into the chamber 19, between the after-body 10 and the stern section 17, the outlets of the conduits 80' being closed by valves 81 which will open rearwardly to permit of the escape of the gases. From chamber 19 the exhaust gases pass through the openings 38 into the hollow coupling 37, and thence through the hollow inner propeller shaft 39 and the stern opening 48 to the sea.

I prefer to cool these highly heated exhaust gases during their passage through the conduits 80', and to that end the conduits 80' are provided with water-jackets 82 extending substantially their entire length, each water-jacket 82 being provided at its forward end with an inlet passage 83 having a flat intake hood 84 opening forwardly, for the purpose of scooping in water as the torpedo runs through the sea. At their rear ends the water is discharged from the water-jackets through passages 85, each provided with an outlet hood 86 opening rearwardly

so that the movement of the torpedo through the sea will tend to reduce the pressure beneath the hoods and thereby accelerate the circulation of water through the jackets.

This cooling of the hot exhaust gases before they enter the propeller shaft 39 prevents the latter being heated to such a degree as to heat the bearings and gears within the stern section 17 so that proper lubrication will be difficult. The cooling of the exhaust gases has also the advantage that the visibility of the wake of the torpedo is thereby reduced.

In the preferred embodiment of the invention, where a pair of bow propellers are used in addition to the stern propellers, a hollow shaft 51 extends forwardly through the motive-fuel flask 3, being joined at its rear end to the forward end of the stub-shaft 27, by means of a coupling 52 of such character that the shafts 27 and 51 will be operatively connected by the longitudinal movement of the flask 3 and the after-body 10 into assembled relation. The rear end of the shaft 51 is journaled in a bearing bushing 53 supported within an outer tube 54 connected at its rear to the bulkhead 5 by a gas-tight connection 55. The projecting rear end of the outer tube 54 is threaded for a jam-nut 54', which is screwed tightly against the rear face of the bulkhead 5. The forward end of the shaft 51 is secured by means of a slip-coupling 60 to the propeller shaft 59, which extends forwardly within the shaft-tube 8 through the war-head, and upon the forward end of which is mounted a propeller 65 secured by a nut 66, the rear end of said propeller shaft 59 being journaled in a bearing 56, having oppositely projecting shaft-arms 68 mounted at their outer ends in a casing 57 secured to the bulkhead 4 of the flask 3, and arranged within the casing 9 mounted upon the rear bulkhead 7 of the war-head. The forward end of the tube 54 is slidably mounted in a gas-tight packing gland 58 in the bulkhead 4, and the parts are so arranged as to permit expansive movement of the bulkhead 4 under pressure of the motive gases therein contained.

An outer propeller shaft 61 surrounds the propeller shaft 59, and is journaled at its rear end within the casing 57 and at its forward end in a bushing 62 in the outer end of the shaft-tube 8. A propeller 63 is mounted upon the end of the outer shaft 61. The forward end of the inner shaft 59 is provided with an enlarged bearing portion 64 which is journaled in the outer shaft 61 and projects forwardly to receive the propeller 65.

The bow propellers 63 and 65 are designed to rotate in opposite directions, and propel the torpedo in a forward direction. The outer shaft 61 is rotated in a direction oppo-

site to that in which the shaft 59 is rotated, by means of a gear cluster mounted within the casing 57, comprising a pair of bevel gears 67 mounted upon the opposite transverse stud-shafts, and a pair of bevel gears 69 and 70 secured to the shafts 59 and 61, respectively, and meshing with the bevel gears 67.

Similarly the propellers 45 and 46 at the rear of the torpedo are driven in opposite directions. The outer propeller shaft 43 is rotated by and reversely to the inner propeller shaft 39 by means of a gear cluster consisting of a pair of bevel gears 47', which 15 rotate about the transverse stud shafts 48', and mesh with the bevel gears 49 and 50 secured, respectively, to the inner shaft 39 and to the outer shaft 43.

As has already been stated, the invention 20 is not limited to the employment of both bow and stern propellers, but includes the use of bow propellers only or stern propellers only.

In the present case, where both bow and 25 stern propellers are used with the gearing indicated, the rotors 20 and 21 are caused to revolve in opposite directions.

In order that the torpedo may cut its way through net-like obstructions, and in order 30 to protect the bow propellers from becoming fouled by such obstructions or by seaweed, etc., the war-head 6 is provided with a propeller guard, the outer edges of which may be sharpened or serrated to form cutters. This guard consists preferably of a 35 pair of flat plates perpendicularly arranged with respect to one another, mounted upon the nose of the war-head, and projecting forwardly therefrom, said plates being cut 40 away as shown at 88 to provide clearance for the propellers. The exposed edges of the plates taper forward from the war-head and the propellers, and terminate in a point 89. The edges of these plates are preferably 45 provided with sharp cutting teeth 90.

It will be understood that the torpedo is provided with suitable steering mechanism, forms of which are well known and need not be described, as well as with suitable mechanism for detonating the charge.

Figs. 3, 4 and 5 illustrate various alternative embodiments of the invention.

Thus in Fig. 3 there is indicated the use only of a rear driving-shaft 328 for driving 55 stern propellers, no bow propellers being used. In this case it will be noted that the rotors 320 and 321 are mounted on a single shaft 322 and revolve in the same direction. The bevel pinion 375 of the reduction gear 60 373 meshes with the bevel pinion 378 secured to the driving-shaft 328, and the bevel pinion 376 of the reduction gear 374 drives the bevel pinion 377 also secured to the driving-shaft 328.

In Fig. 4 there is shown the use of a single 65 driving-shaft 428 for driving both stern and bow propellers. In this case also the rotors 420 on the shaft 422, and 421 on the shaft 423, are driven in the same direction, the reduction gearing being arranged and 70 operating the same as in Fig. 3.

In Fig. 5 are shown separate shafts, the forward shaft 551 driven by the rotor 520 for driving the bow propellers, and the rear shaft 528 driven by the rotor 521 for driving 75 the stern propellers. In this case also the rotors revolve in the same direction.

On account of the several ways in which the shafting may be arranged I desire to be understood that where the term "driving-shaft" is used in the appended claims, unless otherwise indicated, it is understood to cover not only a single shaft but a number of coaxial shafts, either connected or disconnected, and directly or indirectly connected 85 to the reduction gearing.

It will of course be apparent that other modifications may be made in specific embodiments of the invention without essential departure therefrom.

I claim as my invention:

1. In a torpedo, the combination with a longitudinal driving-shaft and a propeller connected to said shaft, of motor mechanism having a plurality of rotors arranged 95 symmetrically on opposite sides of the axial line of said shaft, and gearing arranged between the rotors and connected to the rotors and to the shaft.

2. In a torpedo, the combination with a longitudinal driving-shaft and a propeller connected to said shaft, of motor mechanism having a pair of rotors arranged in static balance on opposite sides of the axial line of said shaft, and gearing arranged 105 between the rotors and in static balance with respect to the axial line of said shaft and connected to the rotors and to the shaft.

3. In a torpedo, the combination with a longitudinal driving-shaft and a propeller 110 connected to said shaft, of motor mechanism having a pair of rotors arranged on opposite sides of the axial line of said shaft, and gearing connected to the said rotors and the said shaft, the said gearing being arranged 115 on opposite sides of the axial line of said shaft and disposed within the space between the said rotors.

4. In a torpedo, motor mechanism having a plurality of turbine rotors arranged symmetrically of the axis of the torpedo and revolving upon axes angular to the torpedo axis, a propeller, and gearing located 120 between the rotors and operatively connected to the propeller.

5. In a torpedo, an annular compartment, motor mechanism arranged in said compartment, a propeller, and gearing arranged in

the space surrounded by said annular compartment and operatively connected to the motor mechanism and to the propeller.

6. In a torpedo, the combination with a body section, of a bow section detachably secured to said body section, a propeller mounted in front of said bow section, a driving shaft for said propeller inclosed in said bow section, and a bearing for said driving shaft carried by the forward end of said body section.

7. In a torpedo, a motor, a hollow shaft driven by the motor through which gases exhausted by the motor are conducted to the exterior of the torpedo, an exhaust conduit establishing communication between the exhaust chamber of the motor and the passage in the hollow shaft, and a concentric water-jacket surrounding the said conduit and having inlet and outlet passages opening through the shell of the torpedo, whereby the temperature of the gases is reduced before they enter the hollow shaft.

8. In a torpedo, a motor, an exhaust conduit for conducting exhaust gases from the motor to the exterior of the torpedo, a water-jacket surrounding said conduit, and inlet and outlet passages in the jacket so arranged that movement of the torpedo through the water will cause water to be forced into the jacket through the inlet passage and discharged through the outlet passage.

9. In a torpedo, a pair of propellers arranged in tandem at the bow of the torpedo and rotatable about a common axis, and means for rotating said propellers in opposite directions.

10. In a torpedo, a pair of stern propellers, a pair of bow propellers, the propellers of each pair being arranged in tandem and rotatable about a common axis, and means for rotating the propellers of each pair in opposite directions.

11. In a torpedo, a motor, forward and aft propeller shafts driven by said motor, forward and aft auxiliary propeller shafts concentric with the said forward and aft propeller shafts respectively, and means for rotating the said forward and aft auxiliary shafts in a direction opposite to the direc-

tion of rotation of the forward and aft propeller shafts respectively.

12. In a torpedo, a war-head, a tube extending longitudinally through the war-head, a propeller mounted in front of the war-head, a driving-shaft for said propeller inclosed within said tube, and a motor arranged to the rear of the war-head and operatively connected to the driving-shaft. 60

13. In a torpedo, a motive-fluid flask, a tube extending through the motive-fluid flask and slidably supported by the wall thereof, a motor, and a driving-shaft connected to the motor and extending through 65 said tube.

14. In a torpedo, a shell comprising a plurality of separate compartments adapted to be joined to form a torpedo shell, a sectional shaft extending through adjoining 70 compartments and divided adjacent the plane of joinder of the compartments, and a coupling for the shaft-sections disposed within the space between the said compartments. 75

15. The combination with a torpedo having a propeller disposed at the bow of the shell, of a guard for the propeller projecting forwardly thereof.

16. A torpedo comprising a shell, a propeller disposed at the bow of the shell, and a guard for the propeller comprising a plurality of forwardly-projecting wedge-shaped plates secured to the bow of the torpedo in angular relation to one another, and 85 provided with openings to permit of the rotation of the propeller.

17. A torpedo comprising a shell, a propeller disposed at the bow of the shell, and a guard for the propeller comprising a forwardly-projecting wedge-shaped plate secured to the bow of the torpedo, the said plate being cut away to provide clearance for the propeller, and having outer cutting edges extending beyond and forward of the 95 propeller.

In testimony whereof I have hereunto set my hand.

HAROLD W. SHONNARD.
